UNITED STATES PATENT OFFICE

WILLIAM S. WILSON, OF WASHINGTON, DISTRICT OF COLUMBIA, ASSIGNOR OF FIFTY
PER CENT TO SHERMAN W. FRAZIER, OF WASHINGTON, DISTRICT OF COLUMBIA

ADVERTISING APPARATUS

Application filed February 9, 1929. Serial No. 338,738.

This invention relates to improvements in advertising apparatus, and more particularly of the illuminated type, one object of the invention being the provision of a built-up 5 multi-sign, in which there is employed a master unit with its prime mover and intermittently revolvable sign carrying member and electric lamp and circuit closer, to be used with one or more auxiliary units carrying 10 each a revolvable sign carrying member, its lamp and transmission and circuit forming member, thus providing a built-up or knock-down type of display sign that can be increased or decreased at will. 15 Another object of the present invention is the provision of a sign of this type which can be used for counter and window display, and in which the signs can be changed at will to provide a simple and practical display 20 sign.

With the foregoing and other objects in view and which will appear as the description proceeds, the present invention resides in the arrangement and combination of parts 25 as herein set forth and more particularly claimed.

In the accompanying drawings:—

Figure 1 is a front elevation of a multiple display sign, including the master unit and 30 two auxiliary units.

Figure 2 is a longitudinal section through the master unit and one of the auxiliary units.

Figure 3 is a cross section on line 3—3 of Figure 2.

Figure 4 is a cross section on line 4—4 of Figure 2.

Figure 5 is a cross section on line 5—5 of Figure 2.

Figure 6 is a view of the electric circuits in 40 diagram.

Referring to the drawings, the numeral 10 designates a base which has mounted thereon a casing 11, preferably made of sheet metal and particularly shaped to house the various 45 necessary parts. The casing 11 is composed of two end walls 12 and 13 and the front 14 is open for displaying the movable signs as will presently appear. The lower strip 15 is for a fixed sign which may be perforated so 50 that light rays from within the casing will

be visible therethrough, or character may be painted or otherwise attached thereto.

A gear box 16 is attached to the end wall 12, and it carries a tubular support 17 for the electric motor 18. The drive shaft 19 is 55 mounted in the support 17, and operates the gearing 20, which contains the maltese cross or star gear 21, whereby the short shaft 21' has imparted thereto intermittent rotary movements during the continuous rotation 60 of the drive shaft. The sign carrying member 22 is connected to and rotated by the shaft 21' attached to the end piece 24 thereof. The end pieces 24 and 25 are connected together by the four rails or strips 26, and the second 65 end piece 25 is provided with the bearing 27 that surrounds the hollow fixed shaft 28, adjustably mounted in the end wall 13 of the casing 11.

Carried upon the inner end of the shaft 28 70 within the member 22 is an electric light or bulb socket 29 for the removable reception of the long show case type electric lamp or bulb 30.

To properly energize the motor and bulb, 75 the latter intermittently and only when the member 22 is stationary, a conductor cord 31 is provided to plug into an outlet, and the switch 32 controls the motor while the switch 33 controls the lighting circuit. Thus 80 the motor can be operated alone to produce an intermittently rotated display sign or the bulb can be lighted intermittently as the sign is intermittently halted; or the signs may be lighted while the motor is inert. 85 Thus providing a sign capable of use in a variety of manners or ways to provide an attractive display.

To accomplish the intermittent energization of the electric light, a switch composed 90 of the fixed and movable contact members 34 and 35 are placed in series with the lamp, and are opened and closed by the rotation of the member 22, said contacts being open when the member is moving and closed when stationary, and in exhibiting position.

In order to permit the member 22 to be the master member of a multiple display sign, the auxiliary casings 36 and 36' are employed 95 and mounted in each is a rotary sign carry- 100

- ing member 22', similar in construction to the member 22 and having the same correlated parts. Carried by the member 22 is a large gear 37 which is accessible through the slot 38 of the casing 11 for the meshing therewith the small intermediate gear 39 bodily carried by the casing 36 or 36', and in mesh with the large gear 40 of the member 22'; while the casing 36' rests upon to cause its gear 39 5 to engage the large gear 40 in the casing 36. In this manner the number of the auxiliary units may be increased or decreased, and the member 22 will at all times constitute the master drive for the auxiliary members 22'. 10 The lamps 41 carried respectively by the casings 36 and 36', are connected in parallel with the lamp 30, through the socket and plug 43 and 44, carried respectively by the lower and upper casings. 15 It will thus be apparent that to increase the present display apparatus from a single unit to a double or triple unit, that the casing 36 can be placed on top of the casing 11, so that the plug enters the socket for the electrical connection, and the small gear 39 20 meshes properly with the large gear below, and that all members 22 and 22' will be rotated together or in synchrony to, as will presently appear, display their signs, while 25 the electric lights of each member will be energized and de-energized simultaneously as the members 22 and 22' are rotated.

In order that signs may be removably carried by the respective members, four to each member, the rails or strips 26, are each so formed as to have the two right angled channels 45 and 45', and the opposite channels 46 and 46'. One channel 45 of one rail 26 and the opposite channel 45' of the next rail 25 for receptacles for the strip 47 of glass, and which may be of any desired shade, while in one channel 46 of one strip 25 and the opposed channel 46' of the next rail 26 is a curved in cross section sheet or strip 48 of transparent or translucent material, preferably celluloid or paper, and upon which is placed the sign to be displayed. This sign may be painted thereon, stencilled or cut, or in fact formed in any desired manner. The glass strips are interposed between the inflammable sign carrying strips and the electric lamps, and thus act as a fire guard.

To provide a means so that the various strips 47 and 48 may be removed without dismantling the members 22 and 22', each casing 11, 36 and 36', at the end remote from the gears, is provided with an opening 49 controlled by a removable lid 50.

In using the present display sign for multiple signs, the strips 47 may be of four different colors for each member, and said members are rotated so that the same color is exhibited through the open front. The motor and light switches are then turned on, and the various members 22 and 22' are rotated

intermittently, while the lights are energized intermittently and only when the members 22-22' are stationary. In this manner, the members 22-22' are illuminated and the signs carried upon the strips 48 are visible with the color display occasioned by the color of the strip 47.

Due to the fact that the strips 48 are easily removable, new signs can be easily inserted to produce a daily changed selling medium, making this apparatus especially desirable for grocery and drug store sales media.

What is claimed, as new, is:—

1. A display apparatus, composed of a master unit and an auxiliary unit cooperating therewith detachably connected thereto from above, a revolvable member mounted in each unit, means for revolving the member of the master unit, and detachable means for connecting the member of the master unit to the member of the auxiliary unit whereby the latter member is rotated from the former.

2. A display apparatus, according to claim 1, in which an electric light is located in each member, and means controlled by the member of the master unit for causing the intermittent and simultaneous energization of the lights of both units.

3. An advertising apparatus, including a base, a master rotatable sign carrying member mounted thereon, an electric motor for driving the same, a second rotatable sign carrying member detachably and operably connected to the first from above and to be driven therefrom, an electric light for illuminating each sign carrying member, means interposed between the motor and the first sign carrying member whereby intermittent movement is imparted to both sign carrying members, and means controlled by the latter to intermittently energize said lights.

4. An advertising apparatus according to claim 3, in which each sign carrying member carries a plurality of signs, and in which the exhibiting period of each sign and the energization of the lights is for a greater period than the movement of the members.

5. An advertising apparatus according to claim 3, in which each sign carrying member comprises two end supports and a plurality of connecting rails, and a protecting sheet and a sign carrying sheet mounted between each pair of adjacent rails, the protecting sheet being near the electric light.

6. An advertising apparatus according to claim 1, in which the revolvable member consists of two end supports and a plurality of rails, and a protecting sheet and sign carrying sheet slidably mounted between each pair of such rails.

7. An advertising apparatus according to claim 1, in which each sign carrying member is composed of two end supports and four rails, and two sheets mounted removably between each pair of rails and in spaced rela-

tion to each other, the sheet nearer the electric light be a transparent or translucent protecting sheet.

8. A display apparatus, including a master unit having a casing; a multiple sign carrying member rotatably mounted therein, and comprising two end supports and four rails connecting the supports to form a cage, and a sheet to carry a sign removably mounted between each pair of rails; an electric motor; and a gearing including a star wheel operably connecting the motor to the multiple sign carrying member and whereby the latter member is intermittently rotated to produce a rapid movement and a sustained sign exhibiting movement to said member.

In testimony whereof I affix my signature.

WILLIAM S. WILSON.
